Primary Examiner — Rashida C. Walshon

(74) Attorney, Agent, or Firm — Smith & Hopen, P.A.;
Paul Murty(57) **CLAIM**

The ornamental design for a cleat cover, as shown and described.

DESCRIPTION

FIG. 1 is a right-and-front-side perspective view of a cleat cover, with seams, ridges, name tags, and a heel tab shown in broken lines.

FIG. 2 is a right-side elevation view thereof.

FIG. 3 is a left-side elevation view thereof.

FIG. 4 is a top plan view thereof.

FIG. 5 is a bottom plan view thereof.

FIG. 6 is a rear elevation view thereof.

FIG. 7 is a front elevation view thereof; and,

FIG. 8 is a right-and-rear-side perspective view thereof.

The subject matter delineated in broken lines, showing ridges, seams, stitching, overlays, name tags, and heel tabs, illustrates environment and forms no part of the claimed design.
